UNITED STATES PATENT OFFICE.

CHARLES D. ANDERSON, OF HARRISBURG, PENNSYLVANIA.

INSOLE AND ARCH SUPPORTER.

Application filed January 6, 1925. Serial No. 867.

This invention relates to new and useful improvements in shoes, and particularly to insoles therefor.

One object of the invention is to provide an insole which is provided with means for supporting the arch of the foot of the wearer of the shoe.

Another object is to provide an insole and arch supporter which are constructed and arranged to permit proper and efficient ventilation, during the movements of the foot, and thereby prevent the supporter and insole from becoming malodorous from perspiration of the foot.

Another object is to provide an arch supporter of such construction that it will automatically adjust itself to the foot of the wearer, and conform to the movements of the foot.

Other objects and advantages will be apparent from the following description when taken in connection with the accompanying drawing.

In the drawing:

Figure 1 is a bottom plan view of an insole equipped with an arch supporter, and constructed in accordance with the present invention.

Figure 2 is a vertical transverse sectional view on the line 2—2 of Figure 1.

Figure 3 is a vertical longitudinal sectional view on the line 3—3 of Figure 1.

Figure 4 is a perspective view of an insert.

Referring particularly to the accompanying drawing, 10 represents the body of the insole, which is shaped to properly fit on the sole and heel of a shoe, and therewithin, and arranged to receive the foot of the wearer thereon. Secured to the lower face of the intermediate portion of the insole 10 are the superimposed layers of soft and pliable leather 11, the one attached directly to the insole being of greatest size, the one outwardly thereof of smaller size, and so on to the outermost of the layers which is the smallest of the series. It will be noted that each of these layers of leather 11 is approximately triangular in outline, with the apex rounded, as shown at 12, and the base inwardly curved, as shown at 13. The layers 11 are attached only at their apex portions, whereby the remaining portions are free for sliding movement with

respect to each other both longitudinally of the insole, and transversely thereof. The arrangement of the layers 11 provide pockets therebetween, into which are arranged to be placed the inserts, such as shown in Fig. 4, and designated by the numeral 14.

As clearly shown in the sectional views Figures 2 and 3, the apex portions, as well as the side portions of the layers 11, are gradually reduced in thickness, or beveled, whereby to produce the greatest thickness of the supporter at the center. By introducing the inserts between the layers 11, the arch supporter may be built up to the desired thickness to suit the foot of the wearer.

As the foot moves, as in walking, the insole will flex, and the layers 11 slide, one over the other, both longitudinally and transversely, with the result that air will be permitted to freely circulate between the layers, and prevent such layers from becoming foul and ill-smelling, from perspiration of the foot.

What is claimed is:

1. The combination with an insole, of an arch supporter comprising superimposed layers connected to each other at their apices, one of the layers having its apex connected to the insole, and inserts between the said layers.

2. The combination with an insole, of an arch support comprising a plurality of approximately triangular layers of material, each layer being attached to its adjoining layers at its apex to provide for free independent flexing movement thereof and ventilation therebetween, the apex of the lowest layer being attached to said insole, and removable inserts between the unattached portions of the layers.

3. The combination with an insole, of an arch supporter of approximately triangular outline secured to the insole at its apex portion and comprising a plurality of approximately triangular leather sheets of progressively diminishing size toward the outside of the series and being connected together at their apex portions only, whereby to permit movement of said sheets about said apices and circulation of air therebetween, during the movements of the foot of the wearer.

In testimony whereof, I affix my signature.

CHARLES D. ANDERSON.
